Application February 2, 1933, Serial No. 654,838,
and in Austria February 15, 1932

18 Claims. (Cl. 179—17)

This invention relates to telephone systems and more particularly to systems including selective party lines.

The object of the invention is to provide a simple, efficient and economical arrangement for controlling the selective association of any one of a plurality of subscribers' stations with a single line, both on incoming and on outgoing calls.

10 According to this invention, in a system having a group of subscribers' stations connected by a single line to a central office, slow-acting relays are provided, one for each station, for disconnecting the other stations upon origination of a call from one of the stations, for disconnecting the other stations on a call incoming to one of the stations, and for disconnecting an associated group of selective impulse-receiving relays from the line upon origination of a call at 15 any station or upon answer of an incoming call at any station. The slow-acting relays are also each operatively responsive to the closure of a ground connection upon the origination of a call at the corresponding station, and the arrangement is such as to prevent the origination of a call at any of the stations after seizure of the line at the central office on a call to any of the stations.

20 A feature of the invention is an arrangement of impulse receiving relays associated with a selective multi-station line and located remote from the central office without local battery supply for controlling the selective signaling of any desired one of the stations. A further feature 25 of this arrangement is the provision of an operating winding and a normally short-circuited winding on the first of two impulse-receiving relays whereby the first relay is rendered slow in releasing to prevent its release upon the receipt 30 of the first impulse (that is, upon the opening of the circuit through the operating winding). The arrangement is such that the operation of the second impulse-receiving relay upon the closing of the impulse circuit at the end of the first 35 impulse is effective to open the short circuit through the holding winding of the first impulse-receiving relay and thus enable the release of the first relay upon receipt of the second impulse. A further feature of this arrangement 40 is the provision of a ring-up relay responsive to ringing current incoming over the line for operatively extending the line to the impulse receiving relays. The reoperation of the ring-up relay in response to ringing current incoming over the 45 line after the station selecting impulses have all

been received is effective to complete a ringing circuit to the selected station; and the response of the called station is effective to operate the slow acting relay individual to that station and thereby disconnect the ring-up and impulse-receiving relays.

The drawing which forms a part of this specification illustrates schematically a portion of a telephone system arranged in accordance with the features of this invention.

Referring to the drawing;

Fig. 1 shows schematically a line L common to five subscribers' stations S1, S2, S3, S4 and S5, and relay equipment associated with the stations and line;

Fig. 2 shows schematically a line-switch LS at the central office individual to the line L and a final selector FS having access to the line L.

Although the arrangement disclosed in the drawing provides for five stations, it is of course understood that the invention is generally applicable to party lines with any number of stations. The telephone station apparatus may be of any standard type and includes impulse sending devices (not shown) and keys designated 1, 2, 3, 4 and 5 for use at their respective stations in originating telephone calls. The relay equipment associated with the line L at the end remote from the central office comprises a ring-up relay 60, impulse-receiving relays 61, 62, 63, 64 and 65 and cut-off relays 11, 21, 31, 41 and 51, one for each of the stations. The stations S1, S2, S3, S4 and S5 are connected to the relay equipment by extension lines designated 10, 20, 30, 40 and 50. The line-switch LS, to which the line L connects at the central office may be of any suitable type and in the drawing is shown as a rotary step-by-step switch having a driving magnet 74, and three banks of terminals 71, 72, 73 and corresponding double-ended wipers; associated apparatus includes the relays 75, 76 and 77. The terminals of the banks of switch LS terminate trunks leading to first selectors; the conductors 79 connected to one set of these terminals represents one of the trunks, the associated first selector not being shown. The line L also terminates at the central office in the banks of final selectors, one of which FS is represented schematically by the three banks 81, 82 and 83; associated apparatus includes the relays 85, 86, 87, 88 and 89. The final selector FS is arranged to repeat dial impulses received after a called line has been seized. The conductors 95 represent the trunk incoming to the selector FS from the 110

banks of preceding selectors having access to this final selector.

To further describe the invention, it will be assumed that the subscriber at station S3 initiates a call by removing the receiver from the switchhook in the usual manner and by also operating the key 3. A circuit is thereby completed from ground through the front contact of key 3, over the lower conductor of extension line 30, winding and inner back contact of cut-off relay 31, conductor 69, middle back contacts of relays 51, 41, 31, 21 and 11 in the order named, over conductor 102 of line L, through the left inner back contact of relay 76 and the winding of relay 75 to battery at the back contact of relay 77. The cut-off relay 31 individual to station S3 and the relay 75 both operate. Upon restoration of key 3 a circuit for holding relays 31 and 75 operated is traced from battery through the back contact of relay 77, winding of relay 75, inner left back contact of relay 76, conductor 102 of line L, middle back contacts of relays 11 and 21, inner front contact and winding of relay 31, lower conductor of extension line 30, back contact of key 3, through the telephone instrument of station S3, back over the upper conductor of extension line 30, outer front contact of relay 31, outer back contacts of relays 11 and 21, conductor 101 of line L, outer left back contact of relay 76, to ground at the right front contact of relay 75. With relay 31 operated, an attempt to initiate a call from any other of the five stations will be ineffective, there being no operating circuit for relays 11, 21, 41 or 51. The operation of relay 31 also prevents operation of the ring-up relay 60 in case the line is selected by some one of the final selectors having access thereto on an incoming call, the connection between the operating winding of relay 60 and conductor 102 being opened at the middle back contact of relay 31. The aforementioned operation of relay 75 initiates the operation of switch LS, to select an idle trunk and first selector, by connecting battery through its inner left front contact, the right back contact of relay 76 and the outer left front contact of relay 75 to the winding of driving magnet 74. Each time the interrupter 78 connects ground to the other end of the winding of magnet 74, the magnet operates thereby advancing the brushes of banks 71, 72 and 73 one step at a time. When an idle trunk is encountered, relay 76 operates in a circuit from ground connected to the sleeve conductor of the associated first selector, through the sleeve terminal of this trunk in bank 73, through both windings of relay 76 in series to battery at the inner left front contact of relay 75. In operating, relay 76 short circuits its own right winding thereby increasing the potential of the sleeve terminal of the selected trunk to prevent seizure of the same trunk by any other line-switch having access thereto. The operation of relay 76 also opens the circuit for operating the driving magnet 74 and extends conductors 101 and 102 of line L through the left front contacts of relay 76 and through the brushes and selected terminals of banks 71 and 72 to the line conductors of the first selector (not shown) to which these terminals are permanently connected. Further extension of the line L in response to the dialing of the number of the desired station, the testing of the called line, the signaling of the station if found idle, and the establishment of the talking path are completed in well known manner. Relay 31 is held operated in series with the exten-

sion line 30 and conductors 101 and 102, the source of talking current for the calling station being located in one of the selective switches employed in establishing the connection; relay 76 holds over the sleeve conductor of the first selector to a holding ground until the connection is released in the usual manner.

Assume next that the line L has been selected and found idle by the final selector FS on a call incoming to one of the stations S1, S2, S3, S4 and S5. The final selector FS is arranged to repeat dial impulses over line L for controlling the selection of the particular called station, the line relay 85 being connected, over the incoming line 95 and through the preceding switches (not shown) to the calling line (not shown). Upon seizure of line L, a circuit is closed from battery through the windings of relay 89, through sleeve brush 83 of selector FS, and through the winding of relay 77 of line-switch LS to ground. Relay 89 operates, short-circuiting its left winding to guard the line L from seizure by any other final selector. Relay 77 thereupon operates, battery being thereby disconnected from conductor 102 of line L to prevent interference with the incoming call by an attempt to originate an outgoing call at any one of the stations. The operating magnets and other apparatus not involved in the description of this invention have been omitted from the selector FS. With line relay 85 operated, the release relay 86 is also operated, and a circuit is closed for operating the ring-up relay 60 of line L to prepare the impulse-receiving relays of line L for response to impulses incoming to and repeated by the line relay 85 of selector FS. The circuit for operating relay 60 is traced from the ringing current source 90, through the back contact of relay 87, left winding and back contact of relay 88, front contact of relay 86, wiper and terminal of bank 81, over conductor 102 of line L, through the middle back contacts of relays 11, 21, 31, 41 and 51 in the order named, conductor 69, through the left back contact of relay 60, condenser 67, and the left winding of relay 60 to ground. Relay 88 does not operate in this circuit. The operation of relay 60 in response to the signaling current from selector FS closes a circuit from ground through its right winding and right front contact, conductor 68, outer back contact of relays 51, 41, 31, 21 and 11 in the order named, conductor 101 of line L, terminal and wiper 82 of selector FS, through the right front contact of relay 85 and inductance 91 to battery. Relay 60 is held operated by the current in this circuit after its inner left contacts open the circuit through the operating winding. With relay 60 operated, the right winding of relay 61 is also energized in a circuit from ground at the left back contact of relay 61, through the right back contact of each of relays 61, 62, 63 and 64 in the order named, outer left front contact of relay 60, right winding of relay 61 to conductor 68, thence to battery through resistance 91 of selector FS as hereinbefore described. The outer right front contact of relay 61 closes before the left back contact opens, thereby maintaining the energization of the right winding of relay 61 independent of the continued operation of relay 60.

When the calling subscriber dials the digit which indicates the particular one of the 5 stations with which a talking connection is desired, relay 85 of the final selector responds. Relay 150

86 is slow to release and remains operated during the receipt of dial impulses. The first release of relay 85 opens the circuit through the right winding of relay 60 and the right winding of relay 61 and closes a circuit for operating relay 87. Relay 87 disconnects the ringing current source 90 from conductor 102 of line L; and being slow in releasing relay 87 remains operated until the entire train of station impulses have been received. Relay 60 releases before relay 85 reoperates at the end of the first station impulse, but relay 61 remains operated due to its short-circuited left winding. When relay 85 reoperates, conductor 101 of line L is reconnected to battery through inductance 91, thereby again energizing the right winding of relay 61 and also energizing the right winding of relay 62; the path for energizing relay 62 is traced from conductor 68, through the inner right back contact of relay 60, right winding of relay 62, inner front contacts of relay 61, to ground at the outer right back contact of relay 60. The operation of relay 62 opens the short circuit around the left winding of relay 61 so that this latter relay may immediately release if a second station impulse is received by relay 85. The release of relay 85 in response to a second impulse opens the circuit through the right windings of relays 61 and 62. Relay 61 releases before relay 85 reoperates, but relay 62 remains operated due to its short-circuited left winding. When relay 85 reoperates after the second station impulse, the re-connection of conductor 101 to inductance 91 causes the re-energization of the right winding of relay 62 and the energization of the right winding of relay 63. The operation of relay 63 opens the short circuit around the left winding of relay 62 so that relay 62 may immediately release if a third station impulse is received by relay 85. The release of relay 85 in response to a third impulse opens the circuit through the right windings of relays 62 and 63. Relay 62 releases before relay 85 reoperates, but relay 63 remains operated due to its short-circuited left winding. When relay 85 reoperates after the third station impulse, the re-connection of conductor 101 to inductance 91 causes the re-energization of the right winding of relay 63 and the energization of the right winding of relay 64. The operation of relay 64 opens the short circuit around the left winding of relay 63 so that relay 63 may immediately release if a fourth station impulse is received. The release of relay 85 in response to a fourth impulse opens the circuit through the right windings of relays 63 and 64. Relay 63 releases before relay 85 reoperates, but relay 64 remains operated due to its short-circuited left winding. When relay 85 reoperates after the fourth impulse, the re-connection of conductor 101 to inductance 91 causes the re-energization of the right winding of relay 64 and the energization of the right winding of relay 65. The operation of relay 65 opens the short circuit around the left winding of relay 64, so that relay 64 may immediately release if a fifth impulse is received by relay 85. The release of relay 85 in response to a fifth station impulse opens the circuit through the right windings of relays 64 and 65. Relay 64 releases before relay 85 reoperates, but relay 65 remains operated due to its short-circuited left winding. When relay 85 reoperates after the fifth station impulse, the right winding of relay 65 is again energized to hold this relay operated. It is appar-

ent, therefore, that after the entire train of station impulses have been received, relays 61 and 62 are held operated if one station impulse is received; that relays 62 and 63 are held operated if two station impulses are received; that relays 63 and 64 are held operated if three station impulses are received; that relays 64 and 65 are held operated if four station impulses are received; and that relay 65 alone is held operated if five station impulses are received. When relay 85 reoperates after the last station impulse has been received, relay 87 releases thereby reconnecting the ringing source 90 to conductor 102 of line L to cause the reoperation of relay 60. Relay 60 is again held operated by the energization of its right winding as hereinbefore described. With relays 61 and 62 operated, a ringing circuit is also established from ground through source 90 over conductor 102 through the middle back contacts of relays 11, 21, 31, 41 and 51 and over conductor 69, through the inner back contact of relay 11 and the winding of relay 11 in parallel with condenser 12, over the lower conductor of extension line 10, key 1 and through the ringer (not shown) at station 1, back over the upper conductor of extension line 10, through the outer right back contact of relay 63, outer right front contact of relay 62, and the inner left front contact of relay 60, over conductor 101 of line L, terminal and brush 105 of bank 82, right front contact of relay 85 and through impedance 91 to grounded battery. With relays 62 and 63 operated, the ringing current path is traced from conductor 69 through the inner back contact of relay 21, winding of relay 21 and condenser 22 in parallel, over extension line 20 and through the ringer at station S2, through the outer right front contacts of relays 63 and 62, and through the inner left front contact of relay 60 to conductor 101. With 115 relays 63 and 64 operated, the ringing current path is traced from conductor 69 through the inner back contact of relay 31, winding of relay 31 in parallel with condenser 32, over extension line 30 and through the ringer at station S3, through the right back contact of relay 65, outer right front contact of relay 64, and through the inner left front contact of relay 60 to conductor 101. With relays 64 and 65 operated, the ringing current path is traced from conductor 69, through the inner left back contact of relay 41, winding of relay 41 in parallel with condenser 42, over extension line 40 and through the ringer at station S4, through the inner right front contact of relay 65, the outer right front contact of relay 64, and through the inner left front contact of relay 60 to conductor 101. And with only relay 65 of the impulse receiving relays operated, the ringing current path is traced from conductor 69, through the inner left back contact of relay 51, winding of relay 51 in parallel with condenser 52, over the extension line 50 and through the ringer at station S5, through the outer right front contact of relays 65 and the outer right back contact of relay 64, and through the left inner front contact of relay 60 to conductor 101. Thus, the particular one of stations S1, S2, S3, S4 and S5, which has been selected by relays 61 to 65, inclusive, in response to the impulses repeated over line L by relay 85 of the final selector, is signaled. Upon removal of the receiver at the called station, the current is increased sufficiently to operate relay 88 of the final selector. Relay 88 locks through its right winding under 150

control of release relay 86 and disconnects the ringing current source 90 from conductor 102. Relay 88 also connects ground through inductance 92 and the left back contact of relay 87 and left front contact of relay 88 to conductor 102 in place of the ringing current source 90, thereby establishing a direct current circuit through that one of the cut-off relays 11, 21, 31, 41 and 51 which is associated with the particular called station. Assuming that station S3 is the called station, the cut-off relay 31 is thus operated by the direct current through its winding after the called subscriber has removed the receiver from the receiver hook.

15 The operation of relay 31 causes the release of relay 60 and the release of relays 63 and 64 and frees the line conductors 101 and 102 of all the relay windings leaving only the extension line 30 and cut-off relay 31 connected to 20 the line conductors 101 and 102. The talking currents are transmitted through condensers 93 and 94 and over line 95. When the connection is released relays 85, 86 and 88 release, in turn; whereupon the brushes of switch FS are restored to normal in the well known manner, relays 89 and 77 being thereby released.

25 The resistance 66, normally short-circuited by the inner right back contact of relay 60, is inserted in series with the right windings of relays 60, 61, 62, 63 and 64 after relay 60 re-operates at the end of the station selection, in order that the cut-off relay of the selected station will receive a large enough current through its winding to insure its operation when the 30 called subscriber answers.

35 It should be noted that the impulse receiving relays 60, 61, 62, 63, 64 and 65 and the cut-off relays 11, 21, 31, 41 and 51 are all operated from a source of current located at the central 40 office, no additional source of current being provided for any of the stations or for the common relay group.

What is claimed is:

1. In a telephone system, a central office, a plurality of subscribers' stations, a line connecting all of said stations to said central office, a group of relays operative in response to an incoming call to select any desired one of said stations, and relays one for each of said stations for disconnecting all of the other stations upon receipt of a call at any one of the stations and for disconnecting all of the other stations upon origination of a call at any one of the stations.

2. In a telephone system, a plurality of subscribers' stations, a line common to said stations, relays one for each of said stations, other relays for said line and common to said stations, and means at each station for operating the corresponding one of said individual relays whereby the remainder of said individual relays and said other relays are disconnected from said line.

3. In a telephone system, subscribers' stations, a line common to a plurality of said stations, relays one for each of said plurality of stations, other relays for said line and common to said plurality of stations, the operation of any one of said individual relays being effective to disconnect the remainder of said individual relays and said other relays from the line, call initiating means at each of said plurality of stations for operating the corresponding one of said individual relays, and means for rendering the operation of said call initiating means ineffective so as to prevent interference with incoming calls.

75 4. In a telephone system, subscribers' stations,

a line common to a plurality of said stations, relays one for each of said plurality of stations, other relays for said line and common to said plurality of stations, the operation of any one of said individual relays being effective to disconnect the remainder of said individual relays and said other relays from the line, call initiating means at each of said plurality of stations for operating the corresponding one of said individual relays, a final selector for seizing said line on a call incoming to any one of said stations, and means for rendering the operation of said call initiating means ineffective.

5. In a telephone system, a line common to a plurality of subscribers' stations, selective relays common to said line, means for seizing said line on a call incoming to any one of said stations, and a relay for said line operative in response to ringing current received over said line for operatively connecting said selective relays to said line.

6. In a telephone system, a line common to a plurality of subscribers' stations, a final selector for extending incoming calls to said line, selective relays common to said line for extending said line to any particular one of said stations, a ring-up relay operative in response to ringing current received over said line for operatively connecting the first of said selective relays to said line, and a direct current circuit including a source of current in said final selector for holding said ring-up relay and for operating the first of said selective relays.

7. In a telephone system, a line common to a plurality of subscribers' stations, a final selector for extending incoming calls to said line, selective relays common to said line for extending said line to any particular one of said stations, a ring-up relay operative in response to ringing current received over said line for operatively connecting the first of said selective relays to said line, a direct current circuit including a source of current in said final selector for holding said ring-up relay and for operating the first of said selective relays, and a normally short-circuited winding for said first selective relay effective to hold said relay operated during a temporary opening of said direct current circuit.

8. In a telephone system, a line common to a plurality of subscribers' stations, a final selector for extending incoming calls to said line, selective relays common to said line for extending said line to any particular one of said stations, a ring-up relay operative in response to ringing current received over said line for operatively connecting the first of said selective relays to said line, a direct current circuit including a source of current in said final selector for holding said ring-up relay and for operating the first of said selective relays, a normally short-circuited winding for said first selective relay effective to hold said relay operated during a temporary opening of said direct current circuit, and means effective upon the closing of said direct current circuit after a first temporary opening thereof for operating the second one of said selective relays.

9. In a telephone system, subscribers' stations, lines, one of said lines being common to a plurality of said stations, a final selector for selecting and connecting with said line on calls incoming to any one of said plurality of stations, selective relays common to said line for selecting and connecting said line to any one of said plurality of stations to the exclusion of the other

- stations, a ring-up relay responsive to signaling current received over said line from said selector for operatively connecting said selective relays to said line, a direct current circuit for holding said 5 ring-up relay operated and for operating the first of said selective relays, impulse transmitting contacts in said selector for alternately opening and closing said circuit, the first opening being effective to release said ring-up relay, and a second 10 normally short-circuited winding for said first selective relay for preventing the release of said first selective relay during the first opening of said impulse contacts. 10. In a telephone system, subscribers' stations, lines, one of said lines being common to a plurality of said stations, a final selector for selecting and connecting with said line on calls incoming to any one of said plurality of stations, selective relays common to said line for selecting 20 and connecting said line to any one of said plurality of stations to the exclusion of the other stations, a ring-up relay responsive to signaling current received over said line from said selector for operatively connecting said selective relays to said line, a direct current circuit for holding said ring-up relay operated and for operating the first of said selective relays, impulse transmitting contacts in said selector for alternately opening and closing said circuit, the first opening being effective to release said ring-up relay, a second normally short-circuited winding for said first selective relay for preventing the release of said first selective relay during the first opening of said impulse contacts, a circuit including a back contact of said ring-up relay and said impulse contacts to operate a second one of said selective relays and hold said first selective relay. 11. In a telephone system, subscribers' stations, lines, one of said lines being common to a plurality of said stations, a final selector for selecting and connecting with said line on calls incoming to any one of said plurality of stations, selective relays common to said line for selecting 40 and connecting said line to any one of said plurality of stations to the exclusion of the other stations, a ring-up relay responsive to signaling current received over said line from said selector for operatively connecting said selective relays to said line, a direct current circuit for holding said ring-up relay operated and for operating the first of said selective relays, impulse transmitting contacts in said selector for alternately opening and closing said circuit, the first opening being effective to release said ring-up relay, a second normally short-circuited winding for said first selective relay for preventing the release of said first selective relay during the first opening of said impulse contacts, and a circuit including a back contact of said ring-up relay and said impulse contacts to operate a second one of said selective relays and hold said first selective relay. 12. In a telephone system, subscribers' stations, lines, one of said lines being common to a plurality of said stations, a final selector for selecting and connecting with said line on calls incoming to any one of said plurality of stations, selective relays common to said line for selecting 50 and connecting said line to any one of said plurality of stations to the exclusion of the other stations, a ring-up relay responsive to signaling current received over said line from said selector for operatively connecting said selective relays to said line, a direct current circuit for holding said ring-up relay operated and for operating the first of said selective relays, impulse transmitting contacts in said selector for alternately opening and closing said circuit, the first opening being effective to release said ring-up relay, a second normally short-circuited winding for said first selective relay for preventing the release of said first selective relay during the first opening of said impulse contacts, a circuit including a back contact of said ring-up relay and said impulse contacts to operate a second one of said selective relays and hold said first selective relay, and means actuated by the operation of said second selective relay for opening the circuit through the second winding of said first selective relay to prevent its release during the first opening of said interrupter contacts. 13. In a telephone system, a central office, a plurality of subscribers' stations, a line connecting all of said stations to said central office, a group of relays operative in response to an incoming call to select any desired one of said stations, relays one for each of said stations for disconnecting all of the other stations upon receipt of a call at any one of the stations and for disconnecting all of the other stations upon origination of a call at any one of the stations, and a source of current at said central office for operating and holding said group relays and said individual relays. 14. In combination a plurality of selective relays, each relay having two windings, one winding of each of said selective relays being normally short-circuited, impulse transmitting means, means for operatively connecting said impulse transmitting means to a first one of said selective relays, a circuit including the interrupter contacts of said impulse transmitter and one winding of said first selective relay for operating said relay, means for actuating said impulse transmitter to alternately open and close its interrupter contacts, and a short-circuit across the other winding of said first selective relay to prevent its release during the first opening of said interrupter contacts. 15. In combination a plurality of selective relays, each relay having two windings, one winding of each of said selective relays being normally short-circuited, impulse transmitting means, means for operatively connecting said impulse transmitting means to a first one of said selective relays, a circuit including the interrupter contacts of said impulse transmitter and one winding of said first selective relay for operating said relay, means for actuating said impulse transmitter to alternately open and close the interrupter contacts, a short circuit across the other winding of said first selective relay to prevent its release during the first opening of said interrupter contacts, and means effective in response to the first opening of said interrupter contacts for connecting one winding of the second of said selective relays in series with said interrupter contacts. 16. In combination, a plurality of selective relays, each relay having two windings, one winding of each of said selective relays being normal-

ly short-circuited, impulse transmitting means, means for operatively connecting said impulse transmitting means to a first one of said selective relays, a circuit including the interrupter contacts of said impulse transmitter and one winding of said first selective relay for operating said relay, means for actuating said impulse transmitter to alternately open and close its interrupter contacts, a short circuit across the other winding of said first selective relay to prevent its release during the first opening of said interrupter contacts, means effective in response to the first opening of said interrupter contacts for connecting one winding of the second of said selective relays in series with said interrupter contacts, and a short circuit across the other winding of said second selective relay to prevent its release during a second opening of said interrupter contacts.

17. In combination a plurality of selective relays, each relay having two windings, one winding of each of said selective relays being normally short circuited, impulse transmitting means, means for operatively connecting said impulse transmitting means to a first one of said selective relays, a circuit including the interrupter contacts of said impulse transmitter and one winding of said first selective relay for operating said relay, means for actuating said impulse transmitter to alternately open and close its interrupter contacts, a short circuit across the other winding of said first selective relay to prevent its release during the first opening of said interrupter contacts, means effective in response to the first opening of said interrupter contacts for connecting one winding of the second of said selective relays in series with said interrupter contacts, a short circuit across the other winding of said second selective relay to prevent its release during a second opening of said interrupter contacts.

ing of said second selective relay to prevent its release during a second opening of said interrupter contacts, and means effective in response to the release of said first selective relay during the second opening of said interrupter contacts for connecting one winding of the third of said selective relays in series with said interrupter contacts.

18. In combination a plurality of selective relays, each relay having two windings, impulse transmitting means, means for operatively connecting said impulse transmitting means to a first one of said selective relays, a circuit including the interrupter contacts of said impulse transmitter and one winding of said first selective relay for operating said relay, means for actuating said impulse transmitter to alternately open and close its interrupter contacts, a short circuit across the other winding of said first selective relay to prevent its release during the first opening of said interrupter contacts, means effective in response to the first opening of said interrupter contacts for connecting one winding of the second of said selective relays in series with said interrupter contacts, a short circuit across the other winding of said second selective relay to prevent its release during a second opening of said interrupter contacts, means effective in response to the release of said first selective relay during the second opening of said interrupter contacts for connecting one winding of the third of said selective relays in series with said interrupter contacts, and a short circuit across the other winding of said third selective relay to prevent its release during a third opening of said interrupter contacts.
